(57) **CLAIM**

The ornamental design for a fingerprint scanner, as shown and described.

DESCRIPTION

FIG. 1 is a perspective view of a fingerprint scanner embodying an aspect of the design;

FIG. 2 is a top view of the fingerprint scanner of FIG. 1; FIG. 3 is a bottom view of the fingerprint scanner of FIG. 1; FIG. 4 is a front view of the fingerprint scanner of FIG. 1; FIG. 5 is a back view of the fingerprint scanner of FIG. 1; FIG. 6 is a right side view of the fingerprint scanner of FIG. 1; and

FIG. 7 is a left side view of the fingerprint scanner of FIG. 1.

In accordance with a second embodiment:

FIG. 8 is a perspective view of a fingerprint scanner embodying another aspect of the design incorporating a decorative illuminated bar;

FIG. 9 is a top view of the fingerprint scanner of FIG. 8; FIG. 10 is a bottom view of the fingerprint scanner of FIG. 8;

FIG. 11 is a front view of the fingerprint scanner of FIG. 8; FIG. 12 is a back view of the fingerprint scanner of FIG. 8; FIG. 13 is a right side view of the fingerprint scanner of FIG. 8; and,

FIG. 14 is a left side view of the fingerprint scanner of FIG. 8.

The subject matter in broken lines is disclaimed and forms no part of the claimed design.

1 Claim, 6 Drawing Sheets
